ISAIAH E. HINDMAN, OF OAKMONT, PENNSYLVANIA, ASSIGNOR TO THE DUFF MANUFACTURING COMPANY, OF PITTSBURGH, PENNSYLVANIA, A CORPORATION OF PENNSYLVANIA.

SCREW-JACK.

1,228,210.

Specification of Letters Patent.

Patented May 29, 1917.

Application filed February 26, 1916. Serial No. 80,629.

To all whom it may concern:

Be it known that I, ISAIAH E. HINDMAN, a citizen of the United States, residing at Oakmont, in the county of Allegheny and State of Pennsylvania, have invented a new and useful Improvement in Screw-Jacks, of which the following is a full, clear, and exact description, reference being had to the accompanying drawings, forming part of this specification, in which:—

10 Fig. 1 is a side elevation partially in section on the line I—I of Fig. 4.

Fig. 2, is a vertical section on the line II—II of Fig. 3.

15 Fig. 3 is a sectional plan view on the line III—III of Fig. 1.

Fig. 4 is a similar view on the line IV—IV of Fig. 1.

20 Fig. 5 is a front view with a portion in section approximately on the line V—V of Fig. 3.

Fig. 6 is a detail view of the shaft of the lowering mechanism.

Fig. 7 is an end view thereof.

25 Fig. 8 is a detail sectional view, on an enlarged scale, of a portion of the mechanism shown in section in Fig. 5, showing the parts in position when the screw jack is moving downwardly under the action of the load.

30 Fig. 9 is a view similar to Fig. 8 of a portion thereof showing the position of the parts when the jack screw is being lowered by the lowering mechanism.

35 Fig. 10 is a detail perspective view of the ends of the shafts for the lowering mechanism and the lock-actuating mechanism.

Fig. 11 is a detail sectional view of a portion of the locking mechanism, and

40 Fig. 12 is an end view of the crank shaft showing the clutch member for actuating the lock releasing shaft and the shaft of the lowering mechanism.

This invention relates to an improvement 45 in self-lowering screw jacks which can safely be lowered at a high rate of speed by means of the load and, at the same time, control the rate of speed of the downward movement thereof.

50 One of the objects of my invention is to provide a jack of this character which is durable and simple of construction and in which the mechanism is arranged to be ac-

tuated step by step by means of a ratchet lever to raise the load. Another object of my invention is to provide locking-mechanism for the jack screw to prevent the downward movement thereof, and which locking mechanism is so arranged that when actuated the jack screw is free to be rotated under the weight of the load to lower it. A further object of my invention is to provide positive means coacting with the locking mechanism to positively lower the load, if for any reason the jack screw should become jammed. Still a further object of my invention is to so arrange the locking mechanism that the jack screw can be quickly raised thereby when raising a light load, or for raising a screw into position under a load.

The precise nature of my invention will be best understood by reference to the accompanying drawings which will now be described, it being premised, however, that various changes may be made in the details of construction and general arrangement of the parts, without departing from the spirit and scope of my invention as defined in the appended claims.

Referring to the accompanying drawings, 80 the reference character 2 designates a base and supported within this base is a hollow stem 3, which may be connected to the base in any desired manner. Connected to the upper portion of the hollow stem is a bushing 4, and connected to this bushing 4 by means of screws 5 is a nut 6. The screws 5, extend through the hollow stem 3 and the bushing 4, and are seated in openings in the nut. The nut 6 and sleeve 4 are 85 fixedly connected to the end of the hollow stem, and rotatably mounted within the nut 6 is a jack screw 7. Connected to the jack screw 7 by means of a key is a bevel gear 8, and 9 is a hood connected to a top plate 10 which is supported by means of ball bearings 11, between the bevel gear 8 and the plate 10. Connected to the lower end of the hood 9 is a shell 12 which is provided with a bushing 13 at the lower end 100 thereof, which is slidably mounted on the hollow stem 3. 14 is a spacing ring connected to the bushing 4 which forms a bearing for the shell 12 and a stop for the shell bushing 13. 15 is a bonnet connected to 105 the side of the hood, and journaled in this

bonnet is a stub shaft 17 having a beveled pinion 18 on the end thereof, which meshes with the bevel gear 8 for actuating the screw 7 to lift the load. The end of this shaft 17 is provided with a hexagonal portion and mounted thereon is a ratchet wheel 19, which is held in position in a socket 20, rotatably mounted on the end of the shaft 17. This socket 20 is arranged to receive the usual lever for actuating the jack to lift the load. Pivotally mounted in the lever 20 is a pawl 21, which is held in engagement with the ratchet teeth of the wheel 19 by means of a spring pressed plunger 22, the arrangement being such that the ratchet wheel is moved in the direction indicated by the arrow on Fig. 5 when the socket lever is moved downwardly, while the pawl will ride over the teeth when the socket lever is moved in the opposite direction. This pawl 21 is provided with a detent 23 which is arranged to be engaged by the plunger 22 to hold the pawl in an elevated position clear of the teeth.

25 The pitch of the threads on the jack screw 7 is inclined sufficiently so that the weight of the various parts supported by the screw will cause the screw to move to its downward position. In order to retain the parts in their elevated positions, I provide a lock which comprises a large spur gear 24 which is pinned to the large bevel gear 8. 25 is a small spur gear which meshes with the spur gear 24 and is fixedly connected to the upper end of a vertical shaft 26 rotatably mounted in the hood 9. 27 is a clutch member splined to the shaft 26 and is adapted to be positively rotated thereby, being held in its downward position by means of a compression spring 28. The lower face of this clutch member is provided with a plurality of teeth which are adapted to engage similar teeth on the upper end of a worm wheel 29, which is loosely mounted on the shaft 26. This worm wheel 29 is engaged by a worm 30 which is keyed to a sleeve 31. This sleeve 31 is rotatably mounted in a bearing 32 in the bonnet, and rotatably mounted within this sleeve 31 is a stub shaft 32^a.

33 is a bushing interposed between the stub shaft 32^a and the sleeve 31 and is provided at one end with a flange 34. The flange 34 is secured within the hood 9, and 55 is interposed between the worm 30 and a spur gear wheel 35 secured to the end of the shaft 32^a. This flange 34 supports one end of the bushing 33, while the other end thereof is supported by the bearing 32 through the medium of the sleeve 31. Mounted within the bearing 32 is a crank shaft 36, provided with a boss 37 and a clutch projection 38, the boss 37 being rotatably mounted in the bearing 32, while 60 the body of the crank shaft 36 is rotatably mounted in a collar 39 secured in the end of the bearing 32. 40 is a compression spring surrounding the crank shaft 36 and interposed between the collar 39 and the boss 37, the spring being adapted to hold the 70 clutch projection 38 against the end of the shaft 32^a. The end of the shaft 36 is provided with a crank 41, while the end of the sleeve 31 is provided with a clutch projection 42 and a recess 42^a, and which projection is adapted to be engaged by the clutch projection 38 on the crank shaft 36.

When raising a load, the ratchet wheel 19 is actuated by means of the socket lever which, through the medium of the gears 18 and 8, will rotate the screw to lift the load, which will in turn actuate the gears 24 and 25, together with the shaft 26 and the clutch member 27, the latter being free to rotate in one direction, namely, the direction for lifting the load, but is prevented from moving in the reverse direction by means of the engagement of the worm wheel with the worm.

When it is desired to lower the jack, the 90 crank 41 is rotated in the direction indicated by the arrow in Fig. 8, and through the connection between the projections 38 and 42 will rotate the sleeve 31, together with the worm 30 and permit the jack screw 95 to move downwardly.

In jacks of this character, it is very desirable to provide means to positively rotate the jack screw to lower it, as I have discovered that the jack screw is liable to become 100 jammed at times, and have therefore devised means co-acting with the locking mechanism to simultaneously rotate the lock, and at the same time positively actuate the screw.

The positive lowering mechanism comprises a spur gear 43 connected to the end of a shaft 44, journaled in bearings in the bonnet 15. This spur gear 43 meshes with the spur gear 35 on the end of the shaft 32^a so that the shaft 44 will be positively rotated when the stub shaft 42^a is rotated, as hereininafter described.

45 is a skew gear mounted on the shaft 44, which meshes with a skew gear 46 connected to the shaft 17. The end of the stub shaft 32^a is provided with a projection 47 which is also adapted to be engaged by the clutch projection 38 on the end of the crank shaft 36, as illustrated in Fig. 9.

Assuming that the jack screw has been elevated and the various parts are in the position shown in Figs. 5 and 8, it being desirable to lower the jack screw, the crank 41 will be rotated counter-clockwise, as indicated by the arrow in Fig. 8, which will rotate the sleeve 31 and permit the jack screw to move downwardly, as hereinbefore described.

If, for any reason, the jack screw should 130

become jammed, the gears 24 and 25 will remain stationary, and the worm wheel 29 will rotate freely on the shaft 26. This free rotation of the parts will be less than 360° and, as shown in the drawings, the crank shaft 36 would be rotated from the position shown in Fig. 8 to that shown in Fig. 9, which is approximately 330°. When the parts move from the position shown in Fig. 10 to that shown in Fig. 9, the clutch projection 38 would rotate the sleeve 31 and the worm 30, and as the projection 38 on the end of the crank shaft moves about the end of the stub shaft 32, it would gradually move to the left. As soon as it reached the position shown in Fig. 9, the projection on the crank shaft would engage the projection 47 on the end of the shaft 32 and at the same time be in engagement with the clutch projection 42 on the sleeve, so that any further rotation of the crank shaft would simultaneously rotate the sleeve 31 and the stub shaft 32. As the ratio of the lock actuating mechanism to the positive mechanism for lowering the jack screw is 1 to 1, it will readily be understood that the parts will be freely rotated by means of the crank 41 to actuate the lock and simultaneously positively rotate the jack screw to lower the load. 30 When it is desired to raise the jack screw very rapidly the crank 41 is rotated clockwise, so that the projection 38 on the crank shaft 36 will engage the opposite side of the projection 42 on the sleeve 31, and rotate the worm 30 and the worm wheel 29. The worm wheel 29 will rotate the shaft 26, and through the medium of the clutch member 27 will rotate the gears 25 and 24, which will, in turn, actuate the jack screw independently of the socket lever raising mechanism.

The advantages of my invention result from the provision of a self lowering screw jack which is provided with a locking device arranged to lock the screw against downward or lowering movement which lock is arranged to be moved in advance of the screw in order to permit the screw to follow the lock, the arrangement being such that the lock can be removed at a predetermined speed by the operator and permit the load to follow the lock. Furthermore, from the provision of screw-actuating mechanism for lowering the screw, which is so interrelated with the locking mechanism that it will be automatically thrown into operation to positively lower the screw if it should become jammed with the one actuating device will put the lowering mechanism into operation and at the same time actuate the locking mechanism.

I claim:

1. A jack having a lifting screw, mechanism for raising the screw, a lock for said screw to prevent the screw from moving

downwardly, and means for actuating the lock and to move the screw downwardly, substantially as described.

2. A jack having a lifting screw, mechanism for raising said screw, a rotary lock 70 for preventing the downward movement of said screw, and means for rotating the lock and positively rotating the screw to lower the screw, substantially as described.

3. A jack having a lifting screw, mechanism for raising said screw, a lock for said screw to prevent the downward movement thereof, means for shifting said lock to permit the return of the screw, and positively actuated means for returning said screw; 80 substantially as described.

4. A jack having a lifting screw, mechanism for rotating said screw to elevate it, a lock for said screw to prevent it rotating in the reverse direction, a one-way clutch between said screw and the lock, and means for rotating the lock and clutch together with the screw to move said screw in the reverse direction; substantially as described.

5. A jack having a lifting screw, mechanism for rotating said screw to elevate it, a lock for said screw to prevent it rotating in the reverse direction, a one-way clutch between said screw and the lock, means for rotating the lock and clutch to permit the 95 screw to move in the reverse direction, and mechanism arranged to be rotated by the lock rotating means to positively rotate the screw in the reverse direction; substantially as described.

6. A jack having a lifting screw, mechanism for rotating the screw to elevate it, a lock comprising a worm and a worm wheel, a one-way clutch member connecting the worm wheel, a second clutch member coacting with the first clutch member to permit said clutch members to be moved relative to each other in one direction, means connected to the last mentioned clutch member and the screw for rotating said clutch member, 110 and means for rotating the other clutch member to permit the screw to be lowered; substantially as described.

7. A jack having a frame, a nut mounted in said frame, a screw coacting with the nut, mechanism for rotating the screw and nut relative to each other in one direction, locking mechanism for preventing reverse movement thereof, means to actuate the locking mechanism to permit the screw and nut 115 to move relative to each other in the reverse direction and means for causing the screw and nut to move relative to each other in the reverse direction; substantially as described.

8. A jack having a frame, a nut mounted in said frame, a screw coacting with the nut, mechanism for rotating the screw and nut relative to each other in one direction, locking mechanism for preventing reverse move- 130

ment thereof, mechanism for rotating the screw in the reverse direction, and means to actuate the locking mechanism and last mentioned screw actuating mechanism to unlock the screw and permit the screw and nut to move relative to each other in the reverse direction; substantially as described.

9. A screw-jack having ratchet mechanism for elevating the screw, a rotary lock 10 for said screw, a one-way clutch interposed between said lock and the screw and adapted to rotate therewith, gearing for rotating the screw in the reverse direction, and means for rotating said screw and the lock to lower the 15 screw; substantially as described.

10. A jack having a lifting screw, gearing for raising the screw, a second set of gearing for lowering the screw and to prevent the screw from rotating under the action 20 of the load, and a clutch connection between said sets of gearings and arranged to permit the gearing for lifting the screw to be actuated without affecting the gearing for lowering the screw, substantially as de- 25 scribed.

11. A jack having a lifting screw, a lock comprising a worm and worm wheel connected to the screw and arranged to prevent it from moving downward, mechanism for elevating the screw, and mechanism for rotating the worm and worm wheel to permit the screw to move downward, said mechanism also being arranged to cause the raising mechanism to move in the reverse direction, substantially as described. 30

12. A jack having a lifting screw, gearing for actuating said screw, a lock comprising a worm and worm wheel for preventing said screw from moving downward, a clutch between said lock and the screw arranged 40 to permit the screw to be elevated but to prevent it from being lowered, and mechanism for simultaneously rotating the lock and the gear wheel in the reverse direction to lower the screw, substantially as described. 45

In testimony whereof, I have hereunto set my hand.

ISAIAH E. HINDMAN.
Witness:
GEO. A. YOUNG.
